UNITED STATES PATENT OFFICE.

ALFRED N. COHEN, OF NEW YORK, N. Y.

FASTENER FOR GLOVES AND OTHER ARTICLES.

SPECIFICATION forming part of Letters Patent No. 270,019, dated January 2, 1883.

Application filed November 7, 1882. (No model.)

To all whom it may concern:

Be it known that I, ALFRED N. COHEN, a citizen of the United States, residing at New York, in the county and State of New York, 5 have invented a new and useful Fastener for Gloves and Similar Articles, of which the following is a specification.

The object of my invention is to provide a fastener for gloves and similar articles made 10 in one piece, adapted to be placed on one side of the opening and permanently attached thereto, and arranged to fasten the glove in connection with the ordinary button-hole.

The invention consists in a fastener composed of a shank having at one end a device 15 for connecting it with the glove and at the opposite end a button pivoted to the shank, so that it can be turned against the shank for the purpose of passing it edgewise through the 20 button-hole, and at right angles to the shank for the purpose of fastening itself in the button-hole.

It also consists in the construction of the 25 button and shank and the devices for holding them together, which will be specifically described hereinafter.

In the accompanying drawings, Figure 1 represents a glove with my improved fastener applied to it; Fig. 2, a section of the same 30 taken on line *x* *x*, showing the manner of attaching it to the glove. Fig. 3 represents a side view, and Fig. 4 an edge view, of the fastener. Figs. 5, 6, 7, and 8 are detailed views 35 of parts of the fastener; and Fig. 9 is an enlarged sectional view of the fastener, showing its construction.

Referring to the drawings, *A* is the shank 40 of the fastener, having at one end a disk, *a*, and tubular rivet *b*. At the opposite end or top it is provided with a slot, *c*, and one side of the 45 said slot is provided with an opening, *d*. The top of the shank is squared off, as plainly shown in Fig. 9. The button *B* is connected with the shank *A* by means of a loop, *e*, through which the parts *f*, forming the top of the shank, are passed, so as to form a kind of pivot, on which the button can be turned sidewise to a

position either at right angles to the shank, or nearly parallel to the same. The button is composed of a cap-plate, *g*, in the concave under side of which is placed a plate, *h*, and a spring-plate, *i*, which is held between the sides of the slot in the collet *k*. The loop *e* projects downward from the collet, and the top of the shank bears against the spring-plate *i*. 50

The fastener is connected with the side of the glove-opening by passing its tubular rivet *b* through the same and riveting its end against the under side of the part of the glove, to which it is attached; or, if preferred, a washer, 60 *l*, may be passed over the tubular rivet, after the latter is passed through the glove, and then riveted against the washer, so that the glove will be clamped between the disk *a* and washer *l*, as shown in Fig. 2. 65

The button can be turned sidewise in either direction on its pivot, and the spring *i* holds it in place. When the button is turned to a position at right angles to the shank the spring *i* presses on the square top of the shank and holds the button firmly in place. 70

To connect the loop *e* with the shank it is passed edgewise through the opening *d*.

I claim—

1. As an improved article of manufacture, a 75 fastener for gloves and similar articles composed of the shank *A*, having a device, substantially as described, for permanently attaching it to the glove, and a button, *B*, pivotally attached to the shank, substantially as shown. 80

2. In combination with a glove, a fastener for the same, composed of the shank *A*, permanently attached to one side of the opening in the glove, and the button *B*, pivotally attached to the shank, substantially as set forth. 85

3. The shank *A*, provided with the slot *c*, opening *d*, and parts *f*, in combination with the collet *k*, provided with the loop *e*, and suitable means for permanently attaching it to a glove, substantially as described.

ALFRED N. COHEN.
